CLAIM

The ornamental design for a blister package, as shown and described.

DESCRIPTION

FIG. 1 is a front elevation view of a blister package showing my new design;

FIG. 2 is a left side elevation view thereof;

FIG. 3 is a right side elevation view thereof;

FIG. 4 is a rear elevation view thereof;

FIG. 5 is a top plan view thereof;

FIG. 6 is a bottom plan view thereof; and,

FIG. 7 is a right front perspective view thereof.

The broken line showing in FIG. 1 represents unclaimed subject matter and forms no part of the claimed design.
